Burke, Fraser & Compte

UNITED STATES PATENT OFFICE.

LLOYD STEVENS, OF NEW YORK, N. Y.

HANDLING OR TRANSFERRING GRAVEL, COAL, &c.

SPECIFICATION forming part of Letters Patent No. 240,051, dated April 12, 1881.

Application filed March 7, 1881. (No model.)

To all whom it may concern:

Be it known that I, LLOYD STEVENS, a citizen of the United States, residing in the city, county, and State of New York, have invented 5 certain Improvements in Handling or Transferring Gravel, Coal, Grits, and Similar Materials, of which the following is a specification.

This invention relates, mainly, to loading vessels, boats, or scows with gravel, grits, coal, 10 sand, &c., but especially the two first, and to unloading them, the principle of operation being the same in both cases, and the apparatus employed substantially the same.

In the application of my invention to loading vessels from the shores of tidal water-ways 15 I excavate a narrow canal near the boat-landing, into which the tide is permitted to ebb and flow, the water-level being the same in the said canal as it is outside or in the sound or river. I prefer to construct the canal parallel 20 with the shore, and to open both ends of it to the main water-way, especially where I can take advantage of natural inlets suited to the purpose; but this is not important, so long as 25 the canal is deep enough to insure a depth of about twelve to fifteen inches of water at low tide. Over this canal I construct a bridge or platform, and in the canal at the side or sides of the bridge I sink a bin or bins, which are 30 not water-tight, but sufficiently tight to prevent the escape of the finest gravel, &c., to be loaded. I employ as many of these bins as I have grades of gravel or grits, and prefer to arrange part at one side of the bridge and part 35 at the other. The water stands in these bins at the same level as outside. The gravel is conveyed from the excavator and screen by carts or other conveyances, and is dumped from the bridge into the bins.

40 On the bridge, as the most convenient place, I set a dredging-pump or injector, run by steam or other power, the machinery being properly housed for protection. From this pump a suction hose or pipe is arranged to depend into either one of the aforesaid bins, and an eduction-pipe is carried out, preferably on a pier or similar structure, to the vessel to be loaded. The pump being set to work, the gravel and water from the bin is forced out to the vessel 45 and into it. As it is desirable that only the gravel shall be deposited in the vessel and not

the water which, of necessity, accompanies it, I do not discharge directly into the vessel, but onto an inclined screen on the vessel's deck. The gravel and water being discharged upon 55 this, the water passes through and overboard, and the gravel, which is unable to pass through, falls into the vessel.

The gravel is removed from the hold of the vessel by means of a dredging-pump in the 60 same manner that it is removed from the bins; but before this can be done it is necessary to admit water to the hold. For this purpose I construct a passage down into the vessel at some convenient place along the side, and a 65 cock below the water-line admits water through the hull into this passage. This cock is arranged to be opened and closed from the deck above, and the influx of water is regulated by a float-valve, as will be more fully described. 70

When the vessel is to be unloaded the cock is opened to flood the hold, and the float-valve will prevent the water from rising above the predetermined height—say fifteen inches—even though the cock be left open. When the 75 gravel has been removed the cock may be closed and the pump kept running until the hold is pumped dry.

For the better understanding of my invention, reference may be had to the accompanying drawings, in which—

Figure 1 is a sectional elevation, and Fig. 2 is a plan, showing my apparatus for loading vessels from bins sunk in a canal on the shore. Fig. 3 is an enlarged sectional view, arranged 85 to illustrate the mechanism employed for admitting water to the material in the hull of the vessel, or into a floating bin, from which the vessel may be loaded. Fig. 4 is a detached view of the discharge-nozzle and its 90 accessories.

Referring to Figs. 1 and 2, A represents the canal before mentioned, excavated near the shore or landing-place; B, the bridge spanning the same; C C, the bins into which the 95 gravel, &c., is dumped from the bridge; D, the dredging-pump or injector operated by an engine, E; a, the induction and b the eduction pipe of the pump, the latter extending out along a pier, F, to a vessel, G, to be loaded. 100

As before stated, the bottom of the canal A is sunk some twelve inches or more below the

level of low tide, so as to insure a minimum depth of water in the same equal to about twelve inches at all times. The employment of a canal of this character for the bins pre-
 5 eludes injury to the bins and machinery from storms; but in some cases the bins might be sunk in the main water-way itself, near the shore, in which case it might be necessary to protect them by means of an embankment,
 10 sheet-piling, or other well-known protection. I prefer to employ a canal of the character de-
 scribed, however, as natural inlets can generally be found that will answer the purpose with very little preparation. The main point
 15 is to provide a means of keeping the bins sup-
 plied with water at all times, so that the end of the suction-pipe may be submerged. The bins may be made of wood or metal, and may have flat or inclined bottoms, as preferred.
 20 To admit the water to them they may have small holes bored in them near the bottom.

The induction-pipes *a* may be fixtures in the bins, and a flexible suction-hose from the pump may be arranged to attach onto any one of them at the level of the platform or bridge *B*. In any case the pipe should have as few an-
 25 gles as possible, and these should not be abrupt.

The eduction-pipe *b* may have a joint in it
 30 to adapt its delivery end to the rise and fall of the tide, or it may have a flexible extremity for the same purpose, as desired; or in some cases where the rise of the tide is not too great this variation in level may be met by moving
 35 the screen up and down.

H is a screen, of some foraminous material, arranged to be set up at the proper incline on the deck of the vessel, so that the water may pass through it and fall onto the deck and flow
 40 overboard, and the material from the bins be shot into the hold of the vessel. As the screen is generally rather fragile and easily injured, and the velocity of the discharged material very great, I provide a splash-plate, *c*, prefer-
 45 ably of iron, to cover that portion of the screen upon which the material is discharged; and to better distribute the material over the screen and lessen the force with which it strikes the screen, I arrange the axis of the nozzle *d* at
 50 an angle with the horizon but little less than that of the screen itself, and flatten the said nozzle, (see Fig. 4,) so as to extend it laterally and give it an elliptic mouth. To prevent the material as it escapes from the nozzle from
 55 scattering and flying about too much, and to lessen the force of discharge, I prefer to pro-
 vide the nozzle with a flexible overhanging apron, *e*, of rubber or other similar material, to receive the force of the stream. In lieu of
 60 this, I may provide the splash-plate with a raised border, so as to form a shallow recep-
 tacle, and discharge into this with a flared nozzle. This would retain a bed of the material to receive the force of the discharge.

65 The arrangement shown in Figs. 1 and 2 is adapted to the shores of tidal water-ways,

where the rise and fall can be easily calculated, and does not vary materially; but for the shores of inland waters, which fluctuate greatly, and the level of which cannot always be re-
 70 lied on or calculated with certainty, I may em-
 ploy a floating bin, as shown in Fig. 3, and load from this into the vessel. I may in such cases mount the dredging-pump and other ma-
 chinery directly upon the deck of the bin, as
 75 shown, and dump the material into the bin from conveyances driven onto it from a pier, or up a staging from the shore, as most con-
 venient.

As it would be impossible to insert the suc-
 tion-pipe of the pump down through the heap of material in the bin to the water at the bot-
 tom, I prefer to suspend a tube, *f*, from the
 80 deck down into the hold to the water-level in the same, and to pass the suction-pipe down
 through this, as shown; but the pipe *f* might form a part of the suction-pipe, and an at-
 tachment be made at the deck with the pump.
 This pipe *f* may be made to swing in gimbals
 85 at the deck.

I is a passage which is built down the side of the bin to a point below the desired level of the water in the hold, and this is provided with a cock, *g*, to admit water to the hold through the side of the bin. This cock may be shut
 90 off in a well-known way by means of a rod, *h*, which extends up to the deck, and it may also be shut off by means of a float, *i*, which plays in an enlarged part of the passage *I*. When the water rises to a predetermined height in
 95 the hold of the bin, the float rises and cuts off the influx of water through the cock; and when the material is all pumped out, and it is desired to remove the water from the bin, the influx may be cut off independently from the
 100 float-valve by means of the rod *h*. It will sel-
 dom be necessary to employ this latter cut-off with the bin, however, except as a precau-
 105 tionary measure, as the water may generally be al-
 lowed to stand in the bin. I may say that the
 110 cock can be of the usual kind, and the float be arranged to close its mouth or outlet when it lifts. The wall of the passage *I* serves to shield the cock *g* and the float.

For a long bin I may employ several depend-
 115 ing pipes, *f*, arranged at intervals, and the suc-
 tion-hose from the pump may be dropped into them successively.

The vessel *G* is provided with precisely the same means for flooding and for removing the material that are shown in the floating bin, and I have considered it unnecessary to du-
 120 plicate them in Fig. 3. Indeed, the floating bin may be considered as a vessel, and may be constructed and employed as a vessel. In the
 125 case of vessels for transporting, however, it may not be expedient to provide each vessel with separate pumping machinery. This may be set on the unloading pier or wharf in such a position that the suction pipe or hose can
 130 be dropped into the hold of the vessel moored at the pier, and the material may be pumped

or forced from the vessel into elevated bins, from which carts or other conveyances may be loaded through chutes.

In lieu of the dredging-pump employed to 5 take up the water and materials, I may employ an injector to take the materials from a heap and force it, mixed with the injected water, to the objective point; but I prefer the dredging-pump arranged as shown.

10 It will be understood, then, that the most essential feature of my invention consists in throwing the prepared gravel and water onto a screen to eliminate the water, and the employment of bins or receptacles for the material to be transferred, and flooding these bins, so that the material, mixed with the water, may be removed by a dredging-pump; and this applies as well to unloading as to loading vessels, the hulls of which may be considered 15 as bins or receptacles capable of being flooded.

I am aware that gravel, mud, and water have been lifted by means of dredging-pumps, and also by means of injectors, and I make no claim to this; but

20 25 What I do claim is—

1. The mode of handling screened or prepared gravel, grits, and similar materials, which consists in forcing the said materials, mixed with water, by means of pumps or injectors, to the objective point, and discharging the same on a screen, to separate the water from the materials, substantially as and for the purposes set forth.

2. The mode of handling gravel, grits, and similar materials, which consists in first depositing said materials in bins or receptacles supplied with water, and then lifting and forcing the water and materials together, by means of a dredging pump or injector, to the objective point, where they are discharged upon a suitable screen and the water separated therefrom, substantially as and for the purposes set forth.

3. As a means of handling gravel, grits, and similar materials, a receiving-bin arranged to 45 be flooded with water, a dredging pump or injector with suitable induction and eduction pipes, to convey or transfer the mixed water and materials, and a suitable screen to receive 50 the discharged materials and separate the water therefrom, substantially as and for the purposes set forth.

4. As a means of flooding a bin or receptacle for the gravel and other materials to be handled or transferred, a passage, *I*, a cock, *g*, 55 arranged to be closed from the deck, and a float, *i*, to control the influx of water at the cock and prevent it from rising above a predetermined height, substantially as set forth.

5. The bin or receptacle for the materials to 60 be handled or transferred, provided with one or more pendent pipes, *f*, extending down to or below the level of the water in the bin or receptacle, to provide a way or passage for the insertion of the suction-pipe of the dredging- 65 pump, substantially as and for the purposes set forth.

6. The combination, with the screen to receive the discharge, of a splash-plate mounted on said screen at the point where the discharge 70 strikes it, substantially as and for the purposes set forth.

7. The combination, with the screen provided with a splash-plate to receive the discharge, of the nozzle of the eduction or discharge pipe, arranged at an angle with the screen less than ninety degrees, so that the discharge may strike said plate obliquely, and thus reduce the force of the blow, substantially 75 as set forth.

8. The combination, with a screen, *H*, provided with a splash-plate, *c*, of the flattened or oval-shaped nozzle *d* of the discharge-pipe *b*, all arranged substantially as and for the purposes set forth.

9. The nozzle of the eduction or discharge pipe provided with a yielding and flexible apron, substantially as and for the purposes set forth.

10. A bin or receptacle for gravel and similar materials provided with means for flooding same and insuring a predetermined depth of water in same, substantially as and for the purposes set forth.

In witness whereof I have hereunto signed 95 my name in the presence of two subscribing witnesses.

LLOYD STEVENS.
